UNITED STATES PATENT OFFICE.

GEORGE ALFRED LAMBERT, OF ORRINGTON, MAINE.

HAMMER.

SPECIFICATION forming part of Letters Patent No. 536,534, dated March 26, 1895.

Application filed October 10, 1894. Serial No. 525,507. (No model.)

To all whom it may concern:

Be it known that I, GEORGE ALFRED LAMBERT, of Orrington, county of Penobscot, and State of Maine, have invented certain new and useful Improvements in Hammers, of which the following is a specification, reference being had to the accompanying drawings.

The object of my invention is to produce in hammers improvements by which the claw 10 is made adjustable, and by which in horse shoers' hammers the claw is specially adapted for wringing off the driven nails in the well known manner.

By the term "hammer" I mean to include 15 any kind of driving implement, as for example, a hatchet, irrespective of any distinctive feature that may belong to the outside of my invention.

In the accompanying drawings: Figure I is 20 a side elevation of one form of hammer partly in section, the claw being turned toward the handle. Fig. II is a side elevation of another and preferred form of my hammer, the claw being shown in full lines turned toward the 25 handle, and in dotted lines turned in the opposite direction. Fig. III is a section on the line X—X of Fig. II, looking downwardly.

Referring to the figures on the drawings: 1 indicates the hammer head and 2 the helve 30 thereof. 3 indicates a stud bolt projecting from the upper end of the hammer head, preferably screw threaded on its extremity, as indicated at 4 and adapted to receive a sink nut 5.

6 indicates a claw of suitable construction, 35 having a body part 7 that is pierced by a central bore 8 that fits closely around the stud bolt 3 and is revolvable thereon, its separation from the stud bolt being prevented by the nut 5.

40 It being the object of my invention to render the claw revolvably spring-actuated, it may be provided, as shown in Fig. I, with a prong 16, to which is fastened at one end a tensile spring 17 secured at the other end to the helve, as by a hook 18. The spring may be, 45 if preferred, concealed within the helve, as shown in that figure in dotted lines. For preventing the escape of the spring from the prong 16 a yielding protector 19 of rubber,

having a concavity 20 on one side and of a thickness to barely permit its introduction 50 between the end of the prong and the claw, may be used. When in place, the protector is held, in consequence of its shape, by the sides of the concavity 20.

55 In Figs. II and III a preferable form of embodiment of my invention is illustrated, in which the body part 7 of the claw 6 is provided with a cam 21. The cam is located so that its highest point or apex 22 comes opposite the claw and its lowest point 23 comes underneath the same. A spring, preferably 60 U-shaped, secured at one end between the hammer head and the helve, as indicated at 25, and projecting at the other end above 65 the cam 21, serves by pressure exerted from above against the surface of the cam to keep the claw normally in the rearward position. For this reason, it preferably carries on its 70 engaging end an anti-friction roller 26 against which the cam works. In practically utilizing the revolvability of the claw upon the hammer head, the bifurcation of the claw is straddled upon a nail, as for example, a horse 75 shoe nail, and the operator, moving the handle in a circle and thereby giving the hammer and claw a crank and connecting rod movement, twists and severs the nail. When the nail is twisted off the claw returns automatically to its natural position, by means 80 of the spring which actuates it.

What I claim is—

1. The combination with a hammer head, of a revolvable claw secured thereto, and spring actuating mechanism in operative relation 85 with the claw and adapted to compel it to assume a determinate normal position, substantially as specified.

2. The combination with a hammer head, stud bolt and nut, of a claw having a bore to fit the stud bolt, and spring actuating mechanism adapted to yieldingly resist the removal of the claw from its normal position and to return the claw to said normal position when the same is released, substantially 95 as specified.

3. The combination with a hammer head and revolvable claw, of a cam upon the claw,

and a spring secured to the head and bearing against the cam to actuate the claw, substantially in the manner and for the purpose specified.

5. 4. The combination with a hammer head, revoluble claw and cam carried on the claw, of a spring secured to the head, and a roller carried on the spring and engaging with the

cam to actuate the claw, substantially as and for the purpose specified.

In testimony of all which I have hereunto subscribed my name.

GEORGE ALFRED LAMBERT.
